UNITED STATES PATENT OFFICE

ERNEST J. BEHLER, OF MICHIGAN CITY, INDIANA

RAIL-TIE STRUCTURE

Application filed July 22, 1930. Serial No. 469,797.

This invention is devoted to certain structural improvements and refinements embodied in the construction of a device which may be collectively entitled a rail tie.

5 The inventive conception comprehends the usage of a composite structure characterized by two primary parts; namely, a metallic anchor, and a pair of companion wooden blocks constituting cushioning means 10 to accommodate and permit the rails to be attached thereto.

In carrying the invention into actual practice, I have selected appropriate parts which when assembled in accordance with the drawings and description, serve to produce a novel organization of exclusive structurally distinguishing features, such as allow renewal or replacement of the wooden blocks from time to time at minimum expense and with 15 reduced labor and time, as compared with similar known prior art structures.

An object is to generally improve upon inventions of this class by providing an arrangement of details, forming a structure 25 which, it is believed, is previously unequaled in the prior art, and is fully sufficient to fulfill the requirements of a structure of this class in a highly satisfactory and practical manner.

30 In the accompanying drawings, in which pictorial views are utilized to portray the complete structure, like numerals are employed to designate like parts:

In the drawings:

35 Figure 1 is an elevational view showing the complete structure imbedded in the track bed with the rails associated therewith.

Figure 2 is a longitudinal sectional view with the cushion blocks in elevation.

40 Figure 3 is an enlarged end elevation of the structure observing the detail in a direction from left to right in Figure 2.

Figure 4 is a top plan view of the complete structure shown in Figure 1.

45 Figure 5 is a plan view of the steel casting or anchor device.

Figures 6 and 7 are perspective views of certain details.

In the drawings, the metallic body is generally represented by the numeral 4. This

is of general elongated rectangular form and somewhat in the nature of a trough. Intermediate its ends and at longitudinally spaced points are integral webs or partitions 5 which function in one instance as buttress elements. 55 These elements 5 also serve to form a receptacle 6 at the approximate center of the device which may, in practice, be assigned to receive a load of dirt, sand or the like to promote more dependable anchorage and to 60 weight the structure in a practical manner.

The opposite ends of the side walls of the channel are bevelled slightly as at 7, the bevels occurring near the top portions. 65 These walls are provided with pairs of opposed vertical grooves 8 which serve as keepers for removable end plates 9. If desired, the upper edge portions of the plates may be slightly bevelled at 10 to correspond with the bevels 7.

The end plates co-operate with the adjacent partitions 5 in defining a pair of duplicate end pockets for reception of the wooden cushioning blocks 11. Incidentally these blocks may be sawed off from complete 75 wooden ties of conventional form. In other words, the ties may be transported to the job intact and then sawed into appropriate lengths to provide these blocks 11.

It will be observed that each block is such 80 as to permit the upper tread surface thereof to project to a plane above the upper edges of the side walls of the channel. Thus, when the rail 12 is fastened in place by the customary spikes 13, the rail base flange will 85 not rest directly on the metal, but will be cushioned by bringing the entire weight to bear upon the wooden block. The resilient properties of the block will serve obviously to provide for the requisite shock absorbing 90 qualities.

Each end plate is formed with a central bolt hole to receive the spike or bolt 14 which is driven into the end of the block to hold it in place firmly in the pocket and against the buttress partition 5. In addition, there is a notch at 15 which facilitates lifting of the end plate through the medium of a crow bar or the like when it is necessary to replace the block. 95

The numerals 16 designate drain ports or openings formed in the bottom of the metal body as shown in Figure 2. In practice, the wooden blocks 11 are sawed from conventional wooden ties on the job and inserted in the receiving pockets defined between the respective or companion partitions 5 and end plates 9.

The end plate is slid down into the grooves 8 and a spike 14 is driven through the opening therein into the adjacent end of the block to hold the block in position. Subsequent to this, the rails 12 may be spiked in place.

From the foregoing description, it will be seen that the structure selected for accomplishing the desired result is characterized by features of surpassing merit and which, in my judgment, are indispensable in a composite tie structure of this class. The use of abbreviated wooden tie elements 11 permits ordinary ties to be utilized and cut to fit the existing standardized pockets in the metal body.

It is thought that persons skilled in the art to which the invention relates will be able to obtain a clear understanding of the invention after considering the description in connection with the drawings. Therefore, a more lengthy description is regarded as unnecessary. Minor changes in shape, size, and rearrangement of details coming within the field of invention claimed may be resorted to in actual practice if desired.

I claim:

35. A structure of the character described comprising an elongated substantially rectangular body member of substantially U-shaped cross section and of uniform width and height throughout, said body member being open at its ends and having drain openings in its bottom and being further provided with pairs of opposed vertical grooves in its side walls adjacent its ends, webs formed integrally with the side walls and bottom of the body member in spaced relation to the ends thereof and to each other, the upper edges of the webs being flush with the upper edges of the body member, blocks removably insertible in the body member from the open ends thereof 40 for abutting engagement, at their inner ends, with the webs, said blocks projecting above the body member and having their other ends disposed adjacent the grooves, and plates removably insertible in each pair of the grooves 45 and anchored to said other ends of the blocks, said plates having notches in their lower edges for the reception of a lifting tool.
50. In testimony whereof I affix my signature.
55. ERNEST J. BEHLER.
